CLAIM

The ornamental design for a bicycle rear storage compartment, as shown and described.

DESCRIPTION

FIG. 1 is an environmental perspective view of a bicycle rear storage compartment showing my new design;
FIG. 2 is a top plan view thereof;
FIG. 3 is a front elevational view thereof;
FIG. 4 is a left side elevational view with the right side being a mirror image thereof; and,
FIG. 5 is a rear elevational view of thereof.
The broken line showing of a bicycle is for illustrative purposes only and forms no part of the claimed design.
